Clarence S. Olsen, Chicago, Ill., assignor to Chicago Printed String Co., Chicago, Ill., a co-partnership

Application December 6, 1945, Serial No. 124,403

Term of patent 14 years

(Cl. D80—9)

To all whom it may concern:

Be it known that I, Clarence S. Olsen, a citizen of the United States, and residing in the city of Chicago, in the county of Cook and State of Illinois, have invented a new, original, and ornamental Design for a Spool Display Rack or Similar Article, of which the following is the specification, reference being had to the accompanying drawings, forming a part thereof.

On the drawings:

Fig. 1 is an end elevational view of a spool display rack showing my new design.

Fig. 2 is a front elevational view thereof.

Fig. 3 is a perspective view of the spool display rack.

I claim:

The ornamental design for a spool display rack or similar article, substantially as shown.
CLARENCE S. OLSEN.
